Des. 222,965
Patented Feb. 15, 1972

222,965

TOILET SEAT

Alexander Kira and George R. Scheuring, Ithaca, N.Y.,
assignors to American Standard Inc., New York, N.Y.

Filed Sept. 15, 1970, Ser. No. 25,017

Term of patent 14 years

Int. Cl. D23—02

U.S. Cl. D23—71

FIG. 1

FIG. 2

FIG.3

FIG.4

FIG.5

FIG 7

FIG. 6

FIG. 1 is a front perspective view of a toilet seat embodying our new design;

FIG. 2 is a side perspective view thereof;

FIG. 3 is a top plan view thereof;

FIG. 4 is a side elevational view thereof;

FIG. 5 is a front elevational view thereof;

FIG. 6 is a rear elevational view thereof;

FIG. 7 is a top plan view of a modified form of the toilet seat shown in FIG. 1.

We claim:

The ornamental design for a toilet seat, substantially as shown and described.
